IGNITION SWITCH

Elmer E. Johnson, Bronson, Mich., assignor to
 H. A. Douglas Mfg. Co., Bronson, Mich., a corporation of Michigan

Application February 24, 1943, Serial No. 476,983

4 Claims. (Cl. 200—155)

This invention relates generally to electrical switches and more particularly has to do with an electric switch used on an automobile or other vehicle.

One particular object of the invention is to provide a substantial switch housing and firmly connecting thereto a contact carrier.

Another object of the invention is to provide a die cast housing or a construction in which the switch casing is provided with an integral tubular bearing.

A further object is to provide improved means for establishing a detachable interlocking connection between the operating means and switching mechanism of the switch.

An additional object is to provide a durable positive acting switch consisting of a very few parts which may be easily and quickly assembled on a production basis.

The drawing annexed hereto illustrates a preferred embodiment of the invention and referring thereto:

Figure 1 is a vertical section taken through the switch;

Figure 2 is an upstanding view of the switch in another position with portions thereof broken away for the purpose of illustrating certain details of construction;

Figure 3 is a transverse section showing certain movable parts of the switch in a predetermined position;

Figure 4 is a rear end view of the switch showing the same in an "off" or "open" position;

Figure 5 is a view similar to Figure 4 showing the bridge means in a position whereby to place the switch in an "on" position to close the circuit; and

Figure 6 is a side view in elevation of a part of a mounting which is adapted to receive and support the switch.

The switch housing 1 is preferably cast so as to provide a durable switch casing 2 and a tubular bearing 3. The casing 2 is preferably made cylindrical and provided with a cylindrical recess 4. The bearing 3 is also preferably made cylindrical in shape but of a diameter somewhat less than the diameter of the casing 2. The bearing 3 is also preferably of a length somewhat greater than the length of the casing 2 and provided with a bore 5. The recess 4 and bore 5 rotatably receive the switching mechanism generally designated 6 and the operating means or shaft 7, respectively. As illustrated in Figure 1, the bore 5 may be provided with a pair of oppositely disposed longitudinally extend-

ing grooves whereby to alleviate friction between the shaft 7 and the bore, or for some other purpose. The recess 4 is counterrecessed or provided with an annular groove 8 which is adapted to receive a contact carrier 9 and a spacer member 10 associated therewith, the latter being constructed of some desirable insulating material.

The tubular bearing portion 3 is preferably provided with a reduced extremity 11 whereby to provide a shoulder 12, the extremity 11 being exteriorly threaded as indicated at 13 so as to receive an internally threaded cap member 14. Any desirable means may be provided whereby to secure the switch with respect to a support, but as herein illustrated the switch is preferably adapted to be secured to the instrument panel of an automobile or other vehicle. As partially exemplified in Figure 6, the panel is provided with a circular aperture 16 and a notch 17 intersecting the aperture 16. The switch is adapted to be connected to the panel mounting by inserting the reduced extremity 11 into the circular aperture 16 from the rear side of the mounting so that the lug 15 on the shoulder 12 is received in the notch 17 whereby to prevent rotation of the switch with respect to the panel. The shoulder 12 is adapted to engage the rear side of the panel mounting and the rear end of the cap 14 is adapted to engage the front side of the mounting so that the mounting is clamped between the shoulder 12 and element 14. The cap 14 may be provided with diametrically disposed holes 18 so that a spanner wrench or other tool may be employed for drawing the cap tightly into place. The cap not only serves as a locking element, but protects the outer end of the housing, excludes foreign matter from entering the housing, and acts to some extent as a bearing and guide for the shaft 7.

The end wall 19 of the cap 14 is preferably provided with a circular aperture 20 which slidably receives a cylindrical enlargement 21 provided on the operating means or shaft 7, above referred to. The outer extremity of the bore 5 is enlarged to some extent and also receives a portion of the enlargement 21. The inner extremity of the shaft 7 is preferably provided with a spring pressed locking element 22 which is adapted to bear against a shoulder 23. The shoulder is formed by counterrecessing the inner end of the cylindrical bore 5, as clearly illustrated in Figure 2. To disconnect the shaft from the bearing it is only necessary to press

the locking element 22 inwardly so as to remove it from the shoulder 23.

The inner extremity of the shaft is also provided with a tongue 24 which extends longitudinally into the switch casing. This tongue may be located wherever desired but is preferably disposed adjacent one side of the longitudinal axis of the switch, and may be semi-circular in cross-section. The inner extremity of the shaft is provided with an axially extending hole 25, preferably diametrically opposite the tongue 24 on the other side of said longitudinal axis. The tongue 24 and the hole 25 constitute means complementary to other means forming a part of the switching mechanism whereby to provide detachable interlocking connections between the switching mechanism generally designated 6 and the shaft 7 and will be described more in detail subsequently.

The inner extremity of the tubular bearing 3 is provided with a plurality of rearwardly extending substantially equally spaced apart detents 26, at least one of which is clearly illustrated in Figure 1. These detents constitute a part of the means employed for positioning the "on" and "off" positions of the switch.

The inner wall of the casing 2 is preferably provided with a pair of inwardly extending abutments 27 spaced apart a predetermined distance for limiting the rotational movement of the switch mechanism. The counterrecess or groove 8 provided adjacent the free extremity of the casing 2 is preferably provided with an inwardly extending lug 28 which cooperates with the contact carrier 9 and spacer 10 to prevent rotation of the latter within the casing 2, and will be alluded to later.

Referring back to the contact carrier 9 and the spacer member 10, the same are preferably made in the form of circular disks and as noted above are received in the annular groove 8. The carrier 9 is provided with a pair of rivet contacts 29 and 30 circumferentially arranged thereon. Each rivet contact includes a cylindrical shank portion projecting through an aperture provided therefor in the carrier 9 and an enlarged cylindrical head or flat contact portion 31 which is received within a round aperture provided therefor in the spacer member 10, the inner contacting faces of the heads of the contacts being disposed substantially flush with the inner planar surface of the spacer member 10 so that the bridge means may slide easily and freely from the spacer 10 onto the contacting surfaces of the contacts 29 and 30 and back onto the spacer. A pair of L-shaped terminal posts are secured to the carrier by means of the rivets 29 and 30 passing through apertures provided therefor in the bases 32 of the posts and oversetting same thereupon as clearly illustrated. Rotation of the posts is prevented by providing each of the base portions 32 with a finger 33 which projects downwardly into an aperture 34 in the carrier 9 as shown in Figure 2. The upstanding portion 35 of each of the terminal posts may be provided with a screw 36 or the equivalent so that conductor wires may be detachably connected to the post. Obviously, if found desirable, electrical connection means other than the rivet contacts and terminal posts illustrated may be employed.

The periphery of the carrier 9 and spacer 10 are preferably notched as indicated at 37 and 38, respectively, whereby to receive the lug 28 above referred to, so as to prevent rotation of the carrier and spacer member with respect to the cas-

ing when the switch is operated. The housing is preferably constructed of a material of sufficient ductility that the free end of the casing 2 may be flanged over and upon the outer surface of the carrier 9 so as to firmly press the carrier 9 and spacer together and the spacer into intimate contact with the shoulder or base of the groove 8 and thereby provide a substantially fluid-tight switch casing.

The switching mechanism generally designated 6 includes, among other things, an actuated member 39 which is rotated through the agency of the operating means or shaft 7. The actuated member 39 includes a round substantially flat base portion 40, having a radially extending integral projection 41 adapted for movement between the pair of abutments or stop portions 27 formed on the inner wall of the switch casing for predetermining the "on" and "off" positions of the switch, as stated above. The base portion 40 is provided with a semicircular aperture 42 and a pair of rearwardly extending struck out centering projections 43 opposite the aperture 42. The portion 40 is further provided with a cylindrical peg 44 disposed diametrically opposite the aperture 42 and more or less between the pair of projections 43. The actuated member 39 and shaft means 7 are detachably interconnected by inserting the tongue 24 of the shaft into the semicircular aperture 42 and the peg 44 into the hole 25 provided adjacent the inner extremity of the shaft as clearly illustrated in Figures 1 and 3, so that there is at least a two-point connection between the operating means or shaft and the actuated means. Obviously, other means may be employed whereby to provide a detachable connection between the parts just referred to, but as herein shown the parts are preferably so constructed and arranged that a part of the operating means projects into the actuated means and a part of the actuated means projects into a part of the operating means.

The base portion 40 of the member 39 is also provided with a pair of axially extending corresponding fingers 45 and a finger 46. These fingers provided adjacent the periphery of the portion 40, are of substantially the same length, and more or less equally spaced apart circumferentially and slidably receive and support the carrier to which the bridge means of the switch is secured. The finger 46 is of a width slightly greater than the widths of the fingers 45 so that the carrier can be fitted onto the fingers in only one rotational relative position.

The base portion 40 of the actuated member 39 is further provided with a first pair of conical depressions or seats 47, a second pair 48, and a third pair 49, the pairs being substantially equally spaced apart circumferentially. The seats 47 through 49 are adapted to cooperate with the rounded detents 26 provided adjacent the inner extremity of the tubular bearing portion 3 in a manner whereby to predetermine the "on" and "off" positions of the switch and will be described more in detail subsequently.

The carrier 50 for the bridge means 51 is preferably in the form of an annular disk of insulating material. Its periphery is provided with a pair of notches 52 and a notch 53 which receive the pair of axial fingers 45 and finger 46, respectively, provided on the member 39 so that the carrier 50 will rotate with the member 39. The bridge means or contact plate 51 is substantially planar in character and preferably generally triangular in shape, the corners thereof being

formed with bosses to provide contacts 54, 55 and 56, projecting from one side of the plate, the latter two contacts being adapted to cooperate with the rivet contacts 29 and 30 for closing the electric circuit. The bridge plate 51 is preferably held against rotation with respect to the carrier 50 by providing the plate with three equally spaced apart rather small protuberances 60 which project laterally from the other side of the plate into apertures provided therefor in the carrier 50 as clearly shown in Figure 1. The contact plate 51 is preferably secured to the carrier 50 in a manner whereby the contacts 54 through 56 are disposed between the notches 52 and 53 provided in the periphery of the carrier and the protuberances 60 are disposed opposite the notches 52 and 53 between the contacts 54 through 56 in order to provide a well-balanced construction. More specifically, the notches, contacts, and protuberances are spaced apart 120 degrees, circumferentially. This arrangement, among other things, permits the bridge plate 51 to be secured to the carrier 50 in any of three positions, and thereby facilitates the assembly.

A helical spring 57 is arranged between the actuated member 39 and the carrier 50. One extremity of this spring receives the pair of projections 43 formed on the base 40 and the projection 24 provided on the operating shaft 7, as clearly illustrated in Figures 1 and 3. The projections 43 and tongue 24 providing means for centering the spring axially in the switch. The opposite extremity of the spring bears against the bridge carrier 50 and since the protuberances 60 are inset with reference to the inner face of the carrier, the spring cannot engage the bridge plate to cause a short circuit. The member 39 is thus urged forwardly so that the detents 26 are received in certain of the seats 47 through 49 and the bridge means 51 is urged rearwardly so that the contacts 54 through 56 will all either bear against the spacer member 10 or the contacts 55 and 56 will engage the rivet contacts 29 and 30, and the contact 54 the spacer, respectively, whereby to close the circuit. Since the contacts 55 and 56 are the only contacts that engage the rivet contacts, the contact 54 will at all times be in engagement with the spacer member. In other words, regardless of the position of the bridge plate on the carrier 50, one of the contacts will always engage the spacer, and the contact in such case does not act as an electrical contact but merely holds the bridge means in balance and prevents rocking thereof.

It will be noted that the radial projection 41 provided on the member 39 is adapted for movement between the abutments or stop portions 27 provided on the switch casing so that when the switch is in an "off" or inoperative position the projection 41 is in engagement with one of the stop portions 27, and when the switch is in an "on" position as evidenced in Figures 3 and 5, the projection 41 engages the other stop portion. Furthermore, when the switch is in the "on" position the three detents 26 provided adjacent the inner extremity of the tubular bearing 3 will cooperate with three of the seats on the actuated member 39. In other words, one seat of each of the several pairs of seats 47, 48 and 49 will cooperate with a detent 26 to hold the switch open, and when the switch is in an "off" position the other seat of each pair will cooperate or receive a detent. Thus means are provided for definitely predetermining the positions of the switch. It will also be noted that the rotational movement

of the operating means and parts movable therewith is relatively short and when the operating means is moved clockwise the switch becomes operative and movement in a counterclockwise direction opens the circuit.

Having thus described my invention, it is obvious that various modifications may be made in the same without departing from the spirit of the invention; and, therefore, I do not wish to be understood as limiting myself to the exact form, construction, arrangement, and combination of parts, herein shown and described.

I claim:

1. In an electric switch, a housing fashioned to provide a switch casing and a bearing, switch mechanism arranged in said casing and operating means disposed in said bearing connectable to said switch mechanism for driving the same, said switch casing being provided with an annular groove forming a shoulder within the casing, a spacer member seated in said groove and bearing against said shoulder, apertures provided in said spacer member, a carrier engaging said spacer member, said carrier member being provided with contacts projecting through the apertures in said spacer member for engagement by bridge means associated with said switching mechanism, and a free extremity of said switch casing being flanged over and upon said carrier member pressing said carrier member against said spacer member and the latter tightly against said shoulder whereby to provide a substantially fluid tight closure for said switch casing.

2. In an electric switch, a casing, a tubular bearing carried by said casing, a carrier carrying contacts mounted on said casing, movable means disposed in said casing carrying bridge means adapted to engage said contacts, operating means arranged in said bearing operatively connected to said movable means, cooperating means provided on said movable means, and means provided adjacent the inner extremity of said tubular bearing extending axially into said casing engageable with said cooperating means for predetermining the position of said bridge means relative to said contacts.

3. In an electric switch, a housing fashioned to provide a switch casing and a bearing joined together, switch mechanism arranged in said casing and operating means disposed in said bearing connectable to said switch mechanism for driving the same, said switch casing being provided with an annular groove forming a shoulder within the casing, a spacer member seated in said groove and bearing against said shoulder, apertures provided in said spacer member, a carrier engaging said spacer member, said carrier member being provided with contacts projecting through the apertures in said spacer member for engagement by bridge means associated with said switching mechanism, a free extremity of said switch casing being flanged over and upon said carrier member against said spacer member and the latter tightly against said shoulder whereby to provide a substantially fluid tight closure for said switch casing, cooperating means provided on said switch mechanism, and means provided adjacent the junction between said casing and said bearing extending axially into said casing engageable with said cooperating means for predetermining the position of said bridge means relative to said contacts.

4. In an electric switch, a die-cast body form-

ing a casing and a tubular bearing, a carrier carrying contacts mounted on said body, movable means disposed in said casing carrying bridge means adapted to engage said contacts, operating means arranged in said bearing operatively connected to said movable means, cooperating means provided on said movable means, and means pro-

vided adjacent the junction between said casing and bearing extending axially into said casing engageable with said cooperating means for predetermineding the position of said bridge means relative to said contacts.

ELMER E. JOHNSON.
